(57) **CLAIM**

The ornamental design for a holder for a handset, as shown and described.

DESCRIPTION

FIG. 1 is a front view of a holder for a handset showing our new design;

FIG. 2 is a rear view thereof;

FIG. 3 is a perspective front view thereof;

FIG. 4 is a perspective rear view thereof;

FIG. 5 is a left side view thereof;

FIG. 6 is a right side view thereof;

FIG. 7 is a top plan view thereof; and,

FIG. 8 is a bottom plan view thereof.

The broken line disclosure in FIGS. 2, 4, 7, and 8 is for illustrative purposes only and forms no part of the claimed design.

1 Claim, 4 Drawing Sheets
